DESIGN FOR A FISHING ROD HANDLE

Rex O. Baubie and Virgil J. McKendry, Detroit,
Mich., assignors to Florida Rod and Manufacturing
Co., Detroit, Mich., a corporation of
Michigan

Application May 16, 1946, Serial No. 129,734

Term of patent 7 years

(Cl. D31—4)

To all whom it may concern:

Be it known that we, Rex O. Baubie and Virgil J. McKendry, citizens of the United States, residing in Detroit, in the county of Wayne, State of Michigan, have invented a new, original, and ornamental Design for Fishing Rod Handle, of which the following is a specification, reference being had to the accompanying drawing, forming a part thereof, wherein:

Fig. 1 is a side elevational view of a fishing rod handle, showing our new design;

Fig. 2 is a top plan view of the fishing rod handle shown in Fig. 1; and

Fig. 3 is a front elevational view of the fishing rod handle shown in Fig. 1.

What we claim is:

The ornamental design for a fishing rod handle, as shown.

REX O. BAUBIE.
VIRGIL J. MCKENDRY.
